HANDBAG

William H. Carroll, Brooklyn, N. Y.

Application April 16, 1949, Serial No. 87,951

2 Claims. (CL. 150—28)

1

This invention relates to handbags of the box-like type carried by ladies either directly or by the use of a shoulder strap. This type is usually made of leather or generally similar material and has only a top opening so that there is no danger of losing the contents when the bag is opened to give access to its interior. This open top is usually closed by a flap or other top closure.

Ladies customarily carry a large number of personal things in this type of handbag including coins, transportation fare tokens, store credit identification devices and other things which the ladies frequently must retrieve in somewhat of a hurry. Since this type of handbag is designed to carry the various pieces and bits of personal property in a jumble, it normally happens that the coins and other devices mentioned have worked their way to the bottom of the handbag when the lady desires to produce them. When she looks down into the handbag, the interior is not only dark but the desired objects are hidden by others above them, all of which makes it very difficult for the lady to pick out what she is looking for. This sometimes causes her embarrassment, particularly when others are waiting for her to transact her business. The incidental delay may also be a cause of annoyance to those waiting their turn behind the lady.

One object of the present invention is to provide a handbag of this top open type and which will eliminate or greatly reduce the lady's problem mentioned above without detracting from the handbag's appearance or rendering its external appearance unconventional.

Another object is to provide a handbag which generally adheres to the type mentioned, yet which permits the lady to see what is in the bottom of the handbag even though it may be concealed by higher objects from direct downward observation through the mouth of the handbag.

A further object is to provide a handbag attaining these desirable objectives without introducing manufacturing complications or making the construction too expensive to comply with sound merchandising economics.

Other objects may be inferred from the following:

A specific example of a lady's handbag of the type described and embodying the features of the invention is illustrated below with the aid of the accompanying drawings for the purpose of explaining the principles and operation of the invention. The principles of the invention may

be incorporated in other forms than are used in the case of this specific example once the principles and operation of the inventive features are understood.

5 In the accompanying drawings:

Fig. 1 is a front view of the handbag showing its conventional exterior appearance and with a small broken-away portion revealing details of the invention that are otherwise concealed;

Fig. 2 is an end view of Fig. 1 with the handbag closed;

Fig. 3 duplicates Fig. 2 excepting that it shows the handbag open;

15 Fig. 4 is a horizontal cross-section looking down in the handbag and taken from the line 4—4 of Fig. 3;

Fig. 5 is an enlarged cross-section taken from the line 5—5 of Fig. 3;

20 Fig. 6 is the same as Fig. 5 excepting that it shows a first modification;

Fig. 7 is the same as Fig. 5 but it shows a second modification;

Fig. 8 again duplicates Fig. 5 excepting that it shows a third modification, and

25 Fig. 9 is a vertical cross-section of the handbag showing the operational features of the invention.

This illustrated handbag includes an inner transparent front wall 1 and an outer non-transparent front wall 2 having their bottom edges interconnected for hinge action and their end edges joined by non-transparent bellows 3. These bellows 3 are adapted to permit the outer wall 2 to lie superimposed on and substantially in contact with the inner wall 1 and to swing therefrom far enough to clear a line of sight transversely downwardly through all portions of the transparent inner wall 1. Other non-transparent walls comprising the end and bottom wall piece or strip 4 and a back wall 5 define a box-like enclosure behind the transparent front wall 1 adapted to contain the customary collection of articles. The back wall 5 is prolonged upwardly to provide a top flap wall 6 adapted to close both the top of the enclosure mentioned and to extend therefrom over both top edges of the two front walls 1 and 2 and at least partially over the outside of the outer front wall 2.

Excepting for the transparent front inner wall 1, all of the wall parts including the bellows 3 may be made from any of the usual materials customarily used to make a lady's handbag of the type described. Natural or synthetic leather or the various plastics are all suitable materials. The junction between the edges of the various wall parts may be secured together in any con-

venient fashion, the illustrative example using leather strand 7 handsewn over the adjacent edges. Proper precautions should be taken to insure an easy hinging action of the wall 2 so that it may swing away from the inner wall 1. The material from which the bellows 3 are made should be relatively light-weight to facilitate swinging of the outer front wall 2 and to permit this wall to close very compactly against the inner transparent wall 1.

Any suitable relatively stout transparent material may be used for the wall 1. In the illustrative example, a piece of relatively thick "Lucite" is used. It should be transparent enough to see through clearly and without confusion. It should have adequate rigidity to support the collection of personal articles within the handbag without bulging outwardly very much, if at all, when the wall 2 is swung outwardly, and it should preferably be unbreakable. Some of the tempered glasses produced by the glass industry may prove unbreakable to a satisfactory degree. The term "unbreakable" is used in the sense that the material should not be easily shattered in the manner an ordinary brittle glass plate might do.

As shown by Fig. 5, the transparent wall 1 may be secured to the end wall 4 and to the bellows 3 by the stitching 7 used to secure all the other wall edge portions together. This is the manner in which the illustrated example is constructed, it being an instance of an extremely high quality lady's handbag using the finest of handbag leathers and a relatively thick piece of "Lucite" with the leather strand 7 hand sewn to complete the assembly. This type of construction requires the drilling of holes through the edges of the transparent panel 1 and is not very appropriate for lower quality products.

With the above in mind, Fig. 6 shows the transparent panel 1 with its bottom and side edges reduced in thickness as at 1a to permit the necessary holes to be punched instead of drilled. Another step toward reducing the cost of the product is illustrated by Fig. 7 wherein as a second modification a strip of relatively thin plastic 1b is cemented to the side and bottom edges of the transparent wall 1. This cementing may be done by actual cement or when the materials used permit it by the use of a common solvent for the wall 1 and the strip 1b. With this construction, the plastic strip 1b may be made sufficiently pliant and thin to permit machine sewing methods to be used. Fig. 7 shows the same hand stitching as is used in the case of the highest quality construction but it is easy to see that, with the strip 1b made thin enough, it would be an easy matter to resort to machine stitching methods.

As a third and final modification, Fig. 8 shows the construction of Fig. 5 excepting that the stitching 7 is replaced by a metal channel 1a which may be in the form of an open top U frame which is compressed by an adequately powerful press so as to frictionally grip the wall 1 between other parts 3 and 4 which must be attached to it. Although the use of such a metal channel may be relatively inexpensive, it is at the same time adaptable to the manufacture of the highest quality products. As a matter of fact, the other modifications may also be said to be in the same category in this respect.

As illustrated by Fig. 9, the handbag may be provided with a bottom wall 8 which slants toward the transparent inner wall 1. This may

be a false bottom as illustrated by Fig. 9 or in some designs the main bottom wall may slant in this fashion. The angularity of inclination should be adequate to shift all of the smaller articles gravitationally against the inner transparent wall 1. This action naturally occurs with any substantial slant when the handbag contents are jiggled naturally when the handbag is carried by the user.

10 The front wall 2 is shown as provided with an appropriate clasp or fastening 9 for fastening the flap 6 flatly against the outer face of said wall. Such a fastening may be needed to prevent the front wall 2 from falling forwardly 15 inadvertently when the handbag is carried. It is conceivable that the flap 6 may be provided with springy characteristics that would by spring tension retain it in position to prevent the wall 2 from falling forward. It is also possible to 20 provide the wall 2 with a spring action that holds it in place against the wall 1 with the user pulling it forwardly when required and the spring arrangement snapping it back in position. Conversely, the wall 2 may be provided with an 25 outwardly directed spring bias with the cover 6 retaining it in position against this spring bias. Without such a spring bias, the wall 2 normally tends to fall forwardly when this is desired if the bellows 3 are provided with adequately flexible 30 characteristics.

In operation, the lady places all of her usual personal paraphernalia in the handbag where it becomes jumbled in the usual fashion. When 35 she wants to get something out of the handbag, such as a coin for example, she merely unfastens the device 9 and lifts the flap 6. In the case of the illustrated example where flexible leather bellows are used, the outward non-transparent panel 2 falls forwardly easily. The bellows 3 should be designed to permit at least a 45° forward swinging of the wall 2 and preferably not more than about 60° forward swinging. These values are variable to some extent. The forward swinging must be adequate to permit the user to see clearly to the bottom of the handbag but it should not be so great as to result in bulky bellows or to make the handbag unduly conspicuous in its action.

With the front wall 2 swinging forwardly, the user can see clearly to the bottom of the bag so that she can spot the coin or other article she is hunting for. The action is illustrated by Fig. 9 where an elusive coin is shown nesting against the bottom of the transparent wall 1 where it has been guided by the slanting or sloping bottom 8. Being in plain sight, it is easy for the lady to retrieve the coin or other object by reaching down into the top of the handbag in the usual fashion between the walls 1 and 5.

It is to be noted that the wall 1 forms the actual working wall of the handbag and embraces the entire front of the device. The outer front wall 2 functions as a cover for the wall 1.

65 Upon the handbag being reclosed, the transparent wall or panel 1 is completely concealed so that the handbag has the usual conventional appearance. Furthermore, the wall 1 is completely protected from dust, dirt or grit which 70 might otherwise obscure its transparency. Many of the most suitable materials as represented by "Lucite" and materials of similar characteristics have a relatively soft surface which is easily scratched by abrasive grit or dust. This harmful action cannot occur with the present inven-

tion due to the complete protection afforded the material.

Although the invention has been emphasized as applicable to ladies' handbags, it is, of course, applicable to handbags used by anyone when the design is of the box-like type adapted to carry various articles in a jumbled condition. However, it is particularly in the ladies' handbag field that the advantages are so apparent. The invention does not restrict the designer or stylist in any fashion, and any handbag material that may be in fashion at the moment may be used. The usual strap arrangement may be used to provide a handle or a shoulder strap or any other usual accessory of this type may be applied without in any way being interfered with by the invention or detracting from the advantages of the invention.

I claim:

1. A handbag having non-transparent back, bottom and side end walls and including inner transparent and outer non-transparent front walls, said front walls having hinge means interconnecting their bottom edges and having bellows joining their side end edges, said bellows being adapted to permit said outer front wall to lie superimposed on and substantially in contact with said inner front wall and to swing therefrom far enough to clear a line of sight transversely through substantially all portions of said inner front wall, said inner front wall and said back, bottom and side end walls defining a box-like enclosure adapted to contain a collection of articles and said inner front wall being rigid enough to support said collection without substantial deformation of said inner front wall, and a top flap wall adapted to close the top of said enclosure and to extend therefrom over the top edges of both of said front walls and partially over the outside of said outer front wall when the latter is superimposed on and substantially in contact with said inner front wall.

2. A handbag having non-transparent back, bottom and side end walls and including inner transparent and outer non-transparent front
